MOBILE KITCHEN BAR

Edward R. Lord, Reading, Mass.

Application April 12, 1956, Serial No. 41,033

Term of patent 14 years

(Cl. D15—8)

FIG. 2

Fig. 1 is a perspective view of a mobile kitchen bar showing my new design; and

Fig. 2 is a rear elevation thereof.

I claim:

The ornamental design for a mobile kitchen bar, substantially as shown.
